(57) **CLAIM**

The ornamental design for a headlight for a vehicle, as shown and described.

DESCRIPTION

This application contains subject matter related to the following co-pending U.S. design patent applications:
Application Ser. No. 29/624,712, filed Nov. 3, 2017 and entitled “Headlight for a Vehicle”;
Application Ser. No. 29/646,403, filed herewith and entitled “Vehicle, Toy, and/or Replicas Thereof”; and
Application Ser. No. 29/646,417, filed herewith and entitled “Headlight for a Vehicle”.

FIG. 1 is a front view of a headlight for a vehicle according to the design;

FIG. 2 is a right perspective view thereof;

FIG. 3 is a left perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
